(57) **CLAIM**

The ornamental design for a reagent dispensing plate, as shown and described.

DESCRIPTION

FIG. 1 is a perspective view of a reagent dispensing plate in accordance with the present invention.

FIG. 2 is a top view of the reagent dispensing plate of FIG. 1.

FIG. 3 is a bottom view of the reagent dispensing plate of FIG. 1.

FIG. 4 is a front view of the reagent dispensing plate of FIG. 1.

FIG. 5 is a cutaway view of the reagent dispensing plate of FIG. 1, taken along line 5-5.

FIG. 6 is a back view of the reagent dispensing plate of FIG. 1.

FIG. 7 is a right end view of the reagent dispensing plate of FIG. 1.

FIG. 8 is a left end view of the reagent dispensing plate of FIG. 1.

FIG. 9 is an exploded view of the reagent dispensing plate of FIG. 1 in combination with a receiving plate; and,

FIG. 10 is a perspective view of the reagent dispensing plate of FIG. 1 in combination with a receiving plate.

Broken lines are used to illustrate features of the reagent dispensing plate which form no part of the claimed design.
